Primary Examiner — Barbara Fox*Assistant Examiner* — Mehri F Bajoul(74) *Attorney, Agent, or Firm* — Thomas A. O'Rourke; Bodner & O'Rourke, LLP(57) **CLAIM**

The ornamental design for a football, as shown and described.

DESCRIPTION

FIG. 1 is a front perspective view of a football showing the new design;

FIG. 2 is a left side view thereof, wherein the right side view, not shown, is a mirror image;

FIG. 3 is a front view thereof, wherein the rear view, not shown, is a mirror image; and,

FIG. 4 is a top view thereof, wherein the bottom view, not shown, is a mirror image.
